SPOOL

Patrick T. Kelley, Bridgeport, Conn.

Application March 24, 1933, Serial No. 662,421

12 Claims. (Cl. 242—119)

This invention relates to spools, reels, bobbins, or like winding devices.

An object of this invention is to provide a spool which is economical to manufacture and is durable in use, and yet be so constructed as to be light in weight.

Another object of this invention is to provide a construction for a spool so that the core and disks or flanges may be made of fibrous materials, such as fibre or impregnated paper.

A further object of this invention is to produce a spool or the like which has no rough parts or crevices on or into which fine threads may extend to be cut or torn thereby.

15 Other features and advantages will herein-after appear.

In the accompanying drawing—

Figure 1 is a perspective view of a spool made in accordance with this invention.

20 Fig. 2 is a longitudinal sectional view of the spool shown in Fig. 1.

Fig. 3 is a sectional view showing the barrel, end flange, and uniting parts expanded.

Fig. 4 shows the parts brought together prior 25 to spinning or deforming the end flange hub.

Fig. 5 shows the end flange hub spun into operative position.

Fig. 6 is a view similar to Fig. 5, but showing the structure modified.

30 Fig. 7 is also similar to Fig. 5, and shows another modified form of the present invention.

Fig. 8 is a perspective view of part of the retaining flange of the device shown in Fig. 7.

As shown in the accompanying drawing, the 35 spool of the present invention comprises a barrel 10 which may, and preferably is, made of impregnated paper so as to be relatively light and inexpensive. The same is true of the end-disks 11, although, of course, both the barrel 10 and the end-disks 11 may be made of fibre, wood, or 40 other suitable material.

When impregnated paper or fibre is used for the barrel and end-disks, the problem of securely fastening the end-disks on to the barrel is quite 45 different from when these parts are made of other materials, and it is the solution of this problem which is an important feature of the present invention.

As shown in the accompanying drawing, the 50 barrel 10 and end-disks 11 are secured together by metal fastening members 12 (Figs. 2 to 5), 12a (Fig. 6), or 12b (Fig. 7), the latter two figures showing modifications of the invention shown in Fig. 2.

55 The fastening member 12 is made of sheet

metal, preferably brass, stamped and drawn so as to have spaced concentric cylindrical portions 13 and 14, the cylindrical portion 13 being the inner one and the cylindrical portion 14 being directly outside the portion 13. These portions 60 are connected by a wall 15 and form between them a laterally open annular groove 16, see Fig. 3. This groove is shaped to receive the end 17 of the barrel 10 so that the inner surface of the outer cylindrical portion 14 engages the outer 65 surface of the end 17 of the barrel while the outer surface of the inner cylindrical portion 13 projects into the tubular barrel 10 for a substantial distance and engages the inner surface of the barrel.

When the members 12 have been applied to the barrel 10 in this manner, they may be anchored thereto by a spun annular rib 18 as shown in Fig. 5, or prongs 19 may be lanced from the cylindrical portion 13 so as to project into the material of 70 which the barrel 10 is formed, as shown in Fig. 6.

After the member 12 has been placed on the end of the barrel 10, the end-disk or wheel 11 may be slid over the outer cylindrical portion 14, and for this purpose the end-disk has a central 75 aperture 20. Preferably, the aperture 20 is of such size as to slidably fit over the portion 14 which forms a hub for the wheel or end-disk 11.

The disk 11 may be moved inwardly over the end of the barrel until its inner face engages a radial 80 flange or disk 21 on the inner end of the portion 14, and when it does so the connecting portion 15 of the member 12 extends beyond the outer face of the disk, as shown in Fig. 4. After this is done, the portion 15 of the member is deformed 85

and pressed toward the end 17 of the barrel 10 and outwardly so as to overlie an outer portion of the disk 11, as shown in Figs. 5 and 6. This may be conveniently done by spinning the material of the portion 15 of the member 12 and flowing it over against the outer face of the wheel 11, and it is convenient to have the disk 11 beveled as at 22 to receive the material spun over. This securely crimps or binds the wheel to the member 12 between the flange 21 and the spun-over flange or shoulder 23.

When the material is hard or brittle, it is preferable that a split ring 24 be inserted in the recess 16 before the end 17 of the barrel 10 is inserted.

As shown in Fig. 4, the ring will take a position 105 against the inner surface of the outer cylindrical portion 14 and, when the spinning and pressing operation is performed, the metal will bend around the ring which thus forms an anvil and prevents the metal from cracking. The pressure 110

and spinning will cause the ring to imbed itself in the corner of the end 17 and extend over into the spun flange 23.

When the material is of a softer nature and not so likely to crack, the ring 24 may be dispensed with as shown in Fig. 6.

In order to prevent fine thread or wire which may be wound on the spool from entering between the disk 21 and the inner surface of the end-disk 11, the present invention provides a circumferential flange 25 on the end of the disk which fits into a circular groove 26 provided in the disk 11, thus avoiding any crevices or notches into which the wire or thread might extend and be caught and 15 broken.

By having the portion 15 extend through the wheel, it may be utilized as a thrust bearing on which the spool rotates when supported on a vertical spindle.

20 In the modification of this invention shown in Fig. 7, the outer cylindrical portion on the fastening member is dispensed with and instead the end-disk 11 slides directly upon and in contact with the end of the barrel 10. This movement of 25 the disk 11 inwardly on the barrel is limited by a sleeve 27 which is slid over the barrel 10 before the disks 11 are applied. The disk is anchored to the barrel by a flange 28 on the member 12b which extends over the end 17 of the barrel and 30 also over a portion of the outer face of the disk 11.

The flange 28 has to extend farther over the central aperture of the disk 11 in the form shown in Fig. 7 because of the omission of the outer cylindrical portion 14. At its end, the flange 28 is 35 preferably provided with a circumferential flange 29 fitting into a groove 30 in the outer surface of the disk 11. To close the space between the end of the sleeve 27 and the inner surface of the disk 11, there is provided a ring 31 of cloth, felt, or 40 other soft material.

The member 12b shown in Fig. 7 may be fastened to the barrel 10 by an annular rib such as the rib 18 shown in Fig. 5, or by the lanced prongs 19 as shown in Figs. 6 and 7.

45 The circumferential flange 29 may, as shown in Fig. 8, be provided with serrations or teeth 32 adapted to penetrate the material of the disk in the groove 30, and thus keep the end-disk 11 from rotating relative to the barrel 10.

50 Within the scope of this invention, bearing portions may be inserted within the members 12 in any suitable manner. As shown, however, the bearings for the spool are constituted by cups 33 which may be slid into the inner cylindrical portion 13 of the member 12 until they are substantially flush with the portion 15 of the member 12.

55 Each cup 33 has a central aperture through which extends an end of a sleeve 34 which may be made of sheet metal rolled into tubular form. 60 After the sleeve is inserted through the cups, its ends 35 may be spun over as shown in Fig. 2. To hold the sleeve against moving back and forth relative to the cups when, due to differences in materials the barrel 10 expands and contracts 65 differently from the sleeve 34, one end of the sleeve 34 is provided with a spun shoulder 36 engaging the inside surface of one of the cups 33.

The members 12, 12a and 12b are provided 70 with central apertures 37 through which the sleeve 34 extends.

Variations and modifications may be made within the scope of this invention and portions of the improvements may be used without others.

75 Having thus described the invention, what is

claimed as new and for which it is desired to obtain Letters Patent, is:—

1. A bobbin, spool, or the like, comprising a tubular barrel; a centrally apertured end-disk; a member having connected concentric cylindrical portions, one within the other and spaced to form between them a laterally open annular recess into which the end of the barrel is pressed, the inner cylindrical portion extending into the central bore of the tubular barrel and the outer cylindrical portion extending through the central aperture of the end-disk and forming a hub therefor; and means for securing the end-disk to said member.

80 2. A bobbin, spool, or the like, comprising a tubular barrel; a centrally apertured end-disk; a member having connected concentric cylindrical portions, one within the other and spaced to form between them a laterally open annular recess into which the end of the barrel is pressed, the outer cylindrical portion extending through the central aperture of the end-disk and forming a hub therefor, the inside end of the outer cylindrical portion terminating in a disk lying against the inside face of the end-disk; a circumferential flange on the disk of the member extending into a circular groove on the inside surface of the end-disk; and means on the outer end of the outer cylindrical portion engaging the outside surface of the end-disk whereby the end-disk is secured between said last-named means and the disk on the member.

85 3. A bobbin, spool, or the like, comprising a tubular barrel; a centrally apertured end-disk; a member having connected concentric cylindrical portions, one within the other and spaced to form between them a laterally open annular recess into which the end of the barrel is pressed, the outer cylindrical portion extending through the central aperture of the end-disk and forming a hub therefor; and means on opposite ends of said hub to secure the end-disk thereto.

90 4. A bobbin, spool, or the like, comprising a tubular barrel; a centrally apertured end-disk; a member having connected concentric cylindrical portions, one within the other and spaced to form between them a laterally open annular recess into which the end of the barrel is pressed, the outer cylindrical portion extending through the central aperture of the end-disk and forming a hub therefor; and means for securing the end-disk to said member.

95 5. A bobbin, spool, or the like, comprising a tubular barrel; a centrally apertured end-disk; a member having connected concentric cylindrical portions, one within the other and spaced to form between them a laterally open annular recess into which the end of the barrel is pressed, the outer cylindrical portion extending through the central aperture of the end-disk and forming a hub therefor, the inside end of the outer cylindrical portion terminating in a disk lying against the inside face of the end-disk; and means on the outer end of the outer cylindrical portion engaging the outside surface of the end-disk whereby the end-disk is secured between said last-named means and the disk on the member.

100 6. A bobbin, spool, or the like, comprising a tubular barrel; a centrally apertured end-disk; and a member having connected concentric cylindrical portions, one within the other and spaced to form between them a laterally open annular recess into which the end of the barrel is pressed, the outer cylindrical portion extending

through the central aperture of the end-disk and forming a hub therefor, the connecting portion between the inner and outer cylindrical portions being deformed after assembly of the end-disk on said hub to engage the outside of the end-disk to secure the latter to the member.

7. A bobbin, spool, or the like, comprising a tubular barrel made of fibrous material; a centrally apertured end-disk made of fibrous material; a sheet metal member having connected concentric cylindrical portions, one within the other and spaced to form between them a laterally open annular recess into which the end of the barrel is pressed; means securing the inner cylindrical portion in the central bore of the tubular barrel; and means on the outer cylindrical portion which extends through the central aperture of the end-disk and forms a hub therefor for securing the end-disk to said member.

8. A bobbin, spool, or the like, comprising a tubular barrel made of fibrous material; a centrally apertured end-disk made of fibrous material; a sheet metal member having connected concentric cylindrical portions, one within the other and spaced to form between them a laterally open annular recess into which the end of the barrel is pressed; means for securing the inner cylindrical portion in the central bore of the tubular barrel; a disk on the inside end of the outer cylindrical portion lying against the inside face of the fibrous end-disk; and a flange spun over from the outer end of the outer cylindrical portion against the outside surface of the end-disk whereby the end-disk is secured between said flange and the disk on the member.

9. A bobbin, spool, or the like, comprising a tubular barrel; an end-disk having a central aperture large enough to permit it to be slid over the end of the barrel; a member having a cylindrical portion extending into the central bore of the tubular barrel and overlying the end of the same; and cylindrical means on the barrel having a shoulder for determining the position of the end-disk on the barrel, said means including a flange integrally connected with said member engaging one surface of the end-disk and cooperating with said shoulder to secure the end-disk to the barrel.

10. A bobbin, spool, or the like, comprising a tubular barrel; an end-disk having a central aper-

ture large enough to permit it to be slid over the end of the barrel; a member having a cylindrical portion extending into the central bore of the tubular barrel and overlying the end of the same; cylindrical means on the barrel integral with said member having a shoulder for determining the position of the end-disk on the barrel; and a flange integrally connected with said member engaging one surface of the end-disk and cooperating with said shoulder to secure the end-disk to the barrel.

11. A bobbin, spool, or the like, comprising a tubular barrel made of fibrous material; a centrally apertured disk made of fibrous material at each end of the barrel; a sheet metal member at each end of the barrel having a hub portion extending through the central aperture of the disk and securing the disk to the barrel end, said sheet metal member having an inner cylindrical portion extending into the bore of the tubular barrel; a cup at each end of the barrel fitting in a cylindrical portion of said sheet metal member and having its bottom substantially flush with the end of the hub portion of the sheet metal member, said cups being apertured; and a sleeve extending through the apertures in said cups and spun over the margins of the same to constitute a core for the spool.

12. A bobbin, spool, or the like, comprising a tubular barrel made of fibrous material; a centrally apertured disk made of fibrous material at each end of the barrel; a sheet metal member at each end of the barrel having a hub portion extending through the central aperture of the disk and securing the disk to the barrel end, said sheet metal member having an inner cylindrical portion extending into the bore of the tubular barrel; a cup at each end of the barrel fitting in a cylindrical portion of said sheet metal member and having its bottom substantially flush with the end of the hub portion of the sheet metal member, said cups being apertured; and a sleeve extending through the apertures in said cups and spun over the margins of the same to constitute a core for the spool, said sleeve being held against endwise movements in both directions relative to one of said cups but being capable of relative movement in one direction relative to the other cup.
